UNITED STATES PATENT OFFICE

2,417,953

HIGH TEMPERATURE ELECTRICALLY-HEATED FURNACE

Simon H. Stupakoff, Latrobe, Pa., assignor to
Stupakoff Ceramic Manufacturing Co., Latrobe,
Pa., a corporation of Pennsylvania

Application June 2, 1944, Serial No. 538,393

2 Claims. (Cl. 13—20)

1

This invention pertains to electrically-heated furnaces, and more particularly to electrically-heated furnaces using resistance heaters, and is for a furnace capable of operating at high temperatures in an oxidizing atmosphere.

According to the present invention, it is proposed to use as the heating elements for the furnace, a ceramic material which is a conductor of the second class. Material available commercially under the trade name "Insulcon" is a typically satisfactory material. Such materials are made from a mixture of rare earth oxides and have a negative coefficient of electrical resistance. They are insulators when cold, but when heated to about 700° C. or above, they will readily conduct electricity and the passage of current therethrough will of course thereafter sustain them at a conducting temperature.

The melting temperature of the conductor will vary according to the ingredients used, but may be in the neighborhood of 2700° C. Being composed of completely oxidized materials, a conductor of this kind is chemically stable when heated in an oxidizing atmosphere up to or near its melting temperature.

For many years, I have tried to use "Insulcon" conductors as a heating means for furnaces intended to operate with an oxidizing atmosphere at temperatures at or near, or possibly somewhat in excess of 2000° C., there being an industrial need for a furnace of this character. However, difficulty has been encountered in providing for the conduction of electrical current to the heaters operating at or above this region of temperature. Platinum is the metal most resistant to oxidation at high temperatures, but platinum has a melting point of approximately 1650° C., so that the temperature of a furnace using these oxide heating elements, where platinum is used to carry current to the elements, is confined to a temperature below 1650° C. Metals which melt at a higher temperature than platinum, such as molybdenum (melting point 2620° C.), or tungsten (melting point 3370° C.), oxidize or burn readily when heated in air or other oxidizing atmospheres, so that such metals are of no value as leads or terminals for "Insulcon" or similar heaters.

According to the present invention, I have found that by using high frequency electrical current, perhaps 100,000 cycles, more or less, electrical current can be conducted from a lead for a reasonable distance through air to the "Insulcon" units. This avoids the necessity for any metal terminals on the "Insulcon" units themselves, and hence enables the furnace to be oper-

ated at a considerably higher temperature in an oxidizing atmosphere than has heretofore been possible.

My invention may be readily understood by reference to the accompanying drawings, which are purely schematic, and in which:

Fig. 1 represents a longitudinal section through a furnace embodying my invention;

Fig. 2 is a transverse section in the plane of line II—II of Fig. 1;

Fig. 3 is a fragmentary view illustrating partly in section and partly in elevation, an arrangement for including the ceramic heaters in a high frequency circuit; and

Fig. 4 is a detail section in the plane of line IV—IV of Fig. 1, showing the relation of the "Insulcon" or other heaters to the source of current supply.

In the drawings, the structure has been illustrated only schematically for the purpose of indicating one manner of employing my invention. In the drawings, 2 designates generally a refractory furnace structure which is here illustrated to be a small capacity or laboratory size of unit. It has a refractory bottom 3, refractory side walls 4, and a refractory top 5, enclosing a chamber C. In the roof of the furnace are transversely extending hangers or inverted piers 5a, also formed of refractory material, and having a plurality of small holes extending transversely therethrough. These holes loosely receive the heating elements or conductors 6. Provision is made for several of these conductors to be supported in parallel relation.

As heretofore indicated, the conductors or elements 6 are conductors of the second class formed of "Insulcon" or a like compound of rare earth oxides having a negative coefficient of electrical resistivity and which are non-conducting when cold, but which become conductors when heated to a temperature at or above 700° C.

The ends of the conductors 6 terminate in spaced relation to water-cooled electrodes 7 and 8, one of these electrodes being at one end of the resistors and one being at the opposite end, the electrodes being spaced from the ends of the resistors in such manner that a reasonably short gap exists between the resistors and the electrodes. The electrodes themselves are illustrated as being formed of metal with a water-circulating space 9 therein. Each electrode has a connection for two water pipes, these being designated 10, so that water may be continuously circulated therethrough, enabling the electrodes to be kept cool enough to prevent damage thereto. In the drawings, the terminals 7 and 8 are shown as

being located entirely within the furnace chamber, but it is understood that provision may be made for locating them otherwise, or surrounding them with heat insulating material to avoid excess loss of furnace heat. The water pipes 10 may also conveniently comprise conducting leads whereby the electrodes may be coupled into a high frequency circuit including the wires 11 and a source of high frequency current 12. By "high frequency" I mean a frequency above the range of audibility and preferably of the order of around 100,000 cycles or more. Any frequency that will enable the required amount of current to transverse the air gap between the electrodes and the ends of the ceramic conductors 6 may be employed. While frequencies considerably in excess of 100,000 cycles may be used, there is little advantage in using ultra-high frequencies.

In use, it is necessary for the rods 6 to be brought up to a conducting temperature before the furnace will operate electrically. This may be done by the use of gas burners or any other appropriate means not shown, which can be employed to bring the furnace up to a temperature of around 700° C. and thereafter removed or the operation thereof discontinued. At this time the high frequency circuit will be energized and current will travel from the electrodes through the air gap at each end thereof into or from the conductors 6, which, according to the amount of current employed, can be operated in an atmosphere of air or other oxidizing atmosphere at a temperature of about 2000° C. or greater, the temperature however being maintained somewhere at a point below the melting point of the conductors around 2700° C.

The heating units themselves are preferably rod-like in form and of relatively small cross section. This section may be, for example, of the order of a quarter of an inch or less. Where the cross section is large, there may be non-uniform temperature conditions within the unit itself due to the tendency of the current to seek a path through the conductor causing overheating in some points, and perhaps underheating in others. The smaller the diameter of the rods, the more nearly the likelihood of there being uniform conductivity across the entire section, and less likelihood of the current seeking a path of less section than the full diameter of the section.

It will of course be understood that the drawing is schematic and that the heating units may be arranged at the bottom or sides of the furnace chamber.

While I have illustrated and described one embodiment of my invention and the method of operating the same, it will be understood that this is merely by way of illustration and that various changes and modifications may be made within the contemplation of my invention and under the scope of the following claims:

I claim as my invention:

1. An electric furnace designed to operate at very high temperatures in an oxidizing atmos- 65

phere, comprising an enclosure, a rod-like heating element supported therein comprising rare earth oxides and having a negative coefficient of electrical resistivity, a pair of terminals of high electrical conductivity each being in proximity to but spaced from different ends of said conductor, means for cooling said terminals, and a high frequency circuit connected across said terminals to pass a high frequency current throughout substantially the entire cross-sectional area of said heating element.

2. An electric furnace designed to operate at very high temperatures in an oxidizing atmosphere, comprising furnace enclosing walls, a plurality of rod-like conductors of the second class supported from a portion of said walls, a pair of hollow terminals of high electrical conductivity, each being in proximity to but spaced from corresponding ends of said plurality of conductors of the second class, means for circulating a cooling fluid through said hollow terminals so as to maintain their temperature substantially lower than that of said second class conductors, and a source of high frequency current connected in series with said terminals for passing a high frequency current throughout substantially the entire cross-sectional area of said rod-like conductors of the second class for maintaining them at very high temperatures after they have been brought up to such temperatures so as to become conducting.

SEMON H. STUPAKOFF.
